(57) **CLAIM**

We claim the ornamental design of an insulated cup, as shown and described.

DESCRIPTION

FIG. 1 is a perspective view of the insulated cup.

FIG. 2 is a bottom view of the insulated cup.

FIG. 3 is a top view of the insulated cup.

FIG. 4 is a front-side view of the insulated cup.

FIG. 5 is a back-side view of the insulated cup.

FIG. 6 is a left-side view of the insulated cup.

FIG. 7 is a right-side view of the insulated cup; and,

FIG. 8 is an unassembled view of the insulated cup.

In the figures, features of the cup drawn in broken lines form no part of the claimed design.
